(57) **CLAIM**

The ornamental design for a set of vehicle pedals, as shown and described.

DESCRIPTION

FIG. 1 is a front, right side perspective view of a set of vehicle pedals, showing my new design;

FIG. 2 is a rear, left side perspective view of the a set of vehicle pedals;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets

FIG. 1

FIG. 2

FIG. 3

FIG. 4

FIG. 5

FIG. 6

FIG. 7

FIG. 8
